UNITED STATES PATENT OFFICE.

JOSEPH S. EASTHAM, OF PORTLAND, OREGON, ASSIGNOR TO WILLAMETTE IRON AND STEEL WORKS, OF PORTLAND, OREGON.

LOAD BINDER FOR LUMBER CARRIERS.

Application filed October 25, 1926. Serial No. 143,982.

This invention relates generally to the lumber industry, and particularly to a means for binding piles of lumber during transportation thereof on what is known to the trade as a lumber carrier.

The first object of this invention is to provide an exceedingly simple and efficient binder for lumber carriers which will completely bind the load in position.

10 The second object is to provide a binder which will automatically limit the height of the pile handled, thereby obtaining ample clearance under the load when moved.

The third object is to eliminate the usual 15 loss of time and money caused by the spilling of loads, especially noticeable with smooth or planed lumber.

The fourth object is to so construct the binder that it will require no additional 20 labor to operate same.

The fifth object is to so construct the binder that it will be easy to manufacture and install and that it has no parts which will 25 be affected by wear during the life of the carrier.

The sixth object is to make same adaptable to any type of lumber carrier with a special regard to those straddling a pile of lumber, which is the type now in common use.

30 The seventh object is to eliminate the usual strains on a lumber carrier caused by wobbling loads, which are ordinarily a big factor in causing the carriers to turn over, or extremely hard on the carrier themselves,

35 or cause undue wear on the tires of the carrier's wheels.

These, and other objects, will become more apparent from the specification following as illustrated in the accompanying drawing, in 40 which:

Fig. 1 is a side elevation of a carrier showing the approximate position at which these binders are placed. Fig. 2 is a transverse section taken along the line 2—2 in Fig. 1. 45 Fig. 3 is an enlarged perspective view showing the elements of the binder.

Similar numbers of reference refer to similar parts throughout the views.

Referring in detail to the drawing, in 50 order to illustrate this invention there is indicated a representative type of carrier including the wheels 10, the forks 11, cross beams 12 and side frames 13 over which is placed a deck 14, upon which is placed the usual power plant and steering mechanism.

Longitudinal and diagonal braces 15 and 16 are placed on the sides of the carrier.

The binder itself consists of angular clips 17 to which is riveted the vertical standard 18, preferably made up of two spaced angle irons having mounted between same, near the upper end, a sheave 19 and having their lower ends joined together by a plate 20 through which is slidably passed an eye bolt 21 on whose lower end is placed a heavy spring 22 which bears against the washer 23, under which is placed a nut 24.

The angles of the standard 18 are riveted or otherwise secured to the diagonal braces 16 by means of an angular clip 25. Attached to the eye bolt 21 is a cable 26 by means of a clamp 27. The cable 26 passes over the sheave 19 and then horizontally across the carrier to a corresponding sheave 19 and fastens to a similar eye bolt 21 on the opposite side of the carrier. That portion of the cable 26 which can engage the lumber 28 is preferably covered with a piece of rubber hose 26^A to prevent the cable from damaging the wood.

It is to be understood that when lumber is handled by these carriers it is piled upon blocks 29 having, in some cases, a plate 30 on the upper side thereof. The carriers themselves are provided with inturned lifting angles 31 which can pick up and carry bodily the load of lumber 28. It will be noted that the cable 26 inside of the rubber hose 26^A is somewhat below the cross beams 12 against which the load should never bear, since under the action of the powerful lifting mechanism the carrier would be self destructive.

The operation of the device is as follows: Assuming that a pile of lumber has been placed on the blocks 29, the operator drives his carrier straddling over the pile and operates his lifting mechanism to raise the angles 31 and lift the load 28 from the ground until it presses against the rubber covered cable with sufficient force to completely bind the load under the tension of the springs 22. It will be noted that there is an angularity between the horizontal portion of the rubber covered cable and its ends which pass over the sheaves 19 causing the load to be held toward the center, as well as downwardly. This results in an ideal condition since in many instances certain of the boards will be higher than others, which would leave the 110

lower boards loose, regardless of the amount of purely downward clamping, but with the use of this flexible and yielding binder it is possible to hold the boards on their edges 5 as well as on their flat sides.

In many instances a workman is apt to build his pile of lumber too high, making it impossible for the operator of the carrier to raise the load high enough to provide 10 ample clearance under the blocks 29. This causes the blocks to catch on obstructions which they would have cleared had they been properly elevated, either destroying the block by tearing same to pieces, or stopping 15 the load with a sudden jolt, or actually pulling the block 29 out of engagement with the angles 31 causing the entire load to be freed, making it impossible to again pick same up without the entire repiling of the 20 load.

With this device, however, if the pile is too high and the carrier is driven over the pile the rubber covered section of the cable 26 merely slides the top boards off of the 25 pile thereby limiting its maximum height to a point which will insure proper road clearance when the load is lifted.

It can be easily understood that when pil- 30 ling lumber of any kind by hand it is exceed- ingly difficult to get all of the boards in close contact with each other. This means that when picked up by a carrier and firmly clamped by a rigid clamp in a downward direction, as is often done, that as the load is 35 jolted around in transit it gradually becomes loose, unless a means is provided for taking up this accumulating slack.

It is for this purpose, as well as to prevent the actual destruction of the binder, due to 40 over-binding, that the springs 22 are em- ployed which automatically take up the slack as the load becomes more compact.

Again, as suggested, if the portion of the cable covered by the hose 26^a is replaced by

a solid member this will clamp on the high 45 spots only leaving the low boards free to slide lengthwise.

I am aware that many forms of load binders have been constructed in the past ranging from the chain which completely encircles the load of the horse drawn vehicle to more recent attempts of clamping the load down between clamps by means of screws and compounded blocks; I therefore do not 50 claim load-binding devices broadly, but I do 55 intend to cover all such forms and modifications of this device as fall fairly within the appended claims.

I claim:

1. A load binder for lumber carriers 60 which are adapted to straddle a pile of lumber and raise same up bodily consisting of a cable mounted transversely across the arch of said carrier having yieldable sup- 65 ports for the ends of said cable.

2. A load binder for lumber carriers con- 70 sisting of a pair of cables adapted to be mounted transversely across the lumber car- rier near the top of its load-bearing com- partment, each of said cables having a sheave 70 outside of each side of the load from which said cable ends extend to a lower fastening having interposed springs between said cables and fastening.

3. In a binder for lumber carriers, the 75 combination of a pair of spaced vertical brackets adapted to be mounted on opposite sides of a carrier, each of said brackets hav- ing a sheave near the top thereof; a cable 80 passing across both of said sheaves; eye bolts passing through the lower end of said brackets and having springs on the lower end 85 thereof and having their eyes secured to said cable, said springs serving to hold said cable in tension at all times; and a rubber covering over that portion of the cable be- tween said sheaves.

JOSEPH S. EASTHAM.
